UNITED STATES PATENT OFFICE.

HARRY CROCKER, OF IOLA, KANSAS.

RETORT-CHARGING APPARATUS.

No. 894,119.

Specification of Letters Patent.

Patented July 21, 1908.

Application filed December 3, 1906. Serial No. 346,133.

To all whom it may concern:

Be it known that I, HARRY CROCKER, a citizen of the United States, residing at Iola, in the county of Allen and State of Kansas, have invented certain new and useful Improvements in Retort-Charging Apparatus, of which the following is a specification.

My invention relates to improvements in retort charging apparatus, such as are employed in smelters for treating ore.

The object of my invention is to provide an apparatus by which a large number of retorts may be economically and quickly charged.

My invention is particularly adapted for use in connection with retorts so assembled as to form a battery comprising horizontal and vertical rows, the mouths of the retorts being disposed substantially in the same vertical plane.

My invention provides a car adapted to travel transversely in front of the retorts, the said car carrying retort charging means which is vertically adjustable on the car so that the charging means may successively charge the vertical rows of retorts.

The novel features of my invention are hereinafter fully described and claimed.

In the accompanying drawings, which illustrate a means of carrying my invention into effect—Figure 1 is a plan view of the apparatus, a portion of the front end of a battery of retorts also being shown. In this view are illustrated two positions of the apparatus, one position being shown in dotted lines. Fig. 2 is a front elevation view of the apparatus, shown disposed in front of a battery of retorts. Fig. 3 is a plan view, enlarged, of a portion of the retort charging mechanism and parts connected therewith. Fig. 4 is a top view, partly broken away, of a portion of the apparatus, and showing one of the retort charging means connected with a retort. Fig. 5 is a longitudinal vertical sectional view, taken on the dotted line *a—b* of Fig. 1. Fig. 6 is a vertical sectional view taken on the dotted line *c—d* of Fig. 4. Fig. 7 is a longitudinal vertical sectional view of the charging tubes and feed screw, taken on the dotted line *e—f* of Fig. 4. Fig. 8 is a horizontal sectional view taken on the dotted line *g—h* of Fig. 6. Fig. 9 is a vertical cross section taken on the dotted line *i—j* of Fig. 6. Fig. 10 is a cross section taken on the dotted line *k—l* of Fig. 3.

Similar characters of reference denote similar parts.

1 denotes a plurality of retorts arranged in a battery comprising a series of vertical and horizontal rows. In front of these 60 retorts and disposed transversely thereto is a track 2 on which is mounted a horizontally movable car 3. Rigidly secured at their lower ends to said car 3 are four vertical posts 4 having secured to their upper ends a 65 horizontal plate 5. Between said posts 4 is a support comprising a framework consisting of two transverse parallel plates 6 and 7, secured to each other by means of four upright posts 8. On the plate 6 are mounted 70 one or more tracks comprising each two parallel rails 9 disposed transversely to the track 2. The rails 9 have preferably a slight inclination upward toward the battery of retorts. On each pair of rails 9 is 75 mounted a second car 10. Each car 10 carries a retort charging mechanism hereinafter described. To prevent the cars 10 from rising from the rails 9, each car has secured to its upper side the lower ends of 80 four upwardly extending posts 11, to the upper ends of which are rotatively secured, one on each post, a plurality of wheels 12, which bear respectively upon the under sides of rails 13, secured to the under side of the 85 plate 7, parallel with the rails 9. As shown in Figs. 4 and 5, a conductor comprising a cylindrical tube 14, is reciprocatively mounted parallel with the plate 7 and intermediate the plates 6 and 7 in the upper end 90 of each bearing 15, of which there are two, which are secured to the upper side of the plate 6. The said bearings 15 are disposed respectively adjacent the upper ends of the two tracks formed by the rails 9. The forward or outer end of each tube 14 is adapted to be connected with the mouth of any one of the retorts 1. The tubes 14 are disposed parallel with the rails 9 and have telescope connection respectively with the forward 100 ends of two tubes 16 provided each adjacent its rear end and on its upper side with a feed opening 17, to which is connected a hopper 18, into which the ore forming the charge is fed. The lower ends of the tubes 16 are 105 secured respectively upon the cars 10. Rotatively mounted in said tubes 16 respectively, are ejecting means comprising preferably two longitudinal feed screws 19, the rear ends of which are rotatively mounted 110

respectively in two bearings secured one upon each car 10.

I will now describe the mechanism by which the feed screws 19 are rotated:—As shown in Fig. 3, on the upper side of the plate 6 is mounted any suitable motor, such as an electric motor 21, to the armature shaft 22 of which is connected a belt 23, mounted on a pulley 24, secured to a horizontal shaft 25, rotatively mounted in upright bearings 26, which are mounted upon the plate 6. Adjacent opposite ends of the shaft 25 are secured respectively two pairs of sprocket wheels 27, each pair having mounted thereon two chain belts 28 which are disposed side by side parallel with the adjacent tube 16. Opposite ends of each pair of belts 28 are mounted respectively on two sprocket wheels 29, rotatively mounted on a horizontal stud 30, secured to a post 31, extending upwardly from and having its lower end secured to the upper side of the plate 6. To the upper side of each car 10 is secured a horizontal plate 32, upon which are mounted two bearings 33, in which is rotatively mounted a horizontal transverse shaft 34, having rigidly secured to it, two sprocket wheels 35, which respectively engage the two adjacent belts 28, which belts, through the sprocket wheels 35, impart rotation to the shaft 34. Said shaft 34 has secured upon it, on the end adjacent the adjacent car 10, a bevel gear wheel 36, which meshes with a bevel gear wheel 37, rotatively mounted on an upright post 38 secured upon the car 10. On the stem of each feed screw 19, to the rear of each tube 16, is a longitudinally slid able sleeve 39, which is provided on its inner side with a longitudinal groove in which is mounted a key 40 fitted in a corresponding longitudinal groove in the periphery of the stem of the feed screw 19. The rear end of the sleeve 39 is conical and fitted to a correspondingly shaped recess in the forward end of the bevel gear wheel 37. Said gear wheel and said sleeve form a friction clutch by which the rotation of the gear 37 may be imparted to the feed screw 19. Hereinafter I will describe the mechanism for throwing the sleeve 39 in and out of engagement with the bevel gear 37.

As before stated the tubes 14 are each longitudinally reciprocative in the bearings 15. The object of such reciprocation is to permit the tubes to be brought forward so as to engage the mouths of the retorts 1 when the retorts are to be charged, and to permit the said tubes to be retracted from said retorts, to enable the car 3 to be moved horizontally to the next row of retorts, or to enable the vertical adjustment of the support carrying the cars 10. Pivoted to the plate 6 below the tubes 14 respectively and to the rear of the bearings 15 respectively are two upwardly extending levers 41, said levers having each

a transverse hole through which extends the adjacent tube 14. Each tube 14 is provided at opposite sides with projections 42 disposed respectively in longitudinal slots 43 provided in the lever 41 which embraces said tube.

Secured to the upper side of the plate 7 are two vertical plates 44 each having arcuate notched upper edges adapted to be engaged respectively by two pawls 45 pivoted one to each of two levers 46, the lower ends of which are pivoted respectively to the plates 44. Two hand holds 47 are pivoted one to each lever 46. Two links 48 are pivoted at their upper ends to the handholds 47 respectively, the lower ends of said links being pivoted to the pawls 45 respectively. The levers 41 extend through two slots in the plate 7, said slots being denoted by 49. Two rods 50 are connected at their forward ends to the upper ends of said levers 41 respectively, the rear ends of said rods 50 being pivoted respectively to the two levers 46. By reciprocating the levers 46, the tubes 14 may be moved forward and backward for engagement with and disengagement from the retorts 1. The pawls 45 engaging the plates 44 retain the levers 46 fixed in the positions in which they may be placed. By properly swinging the handholds 47, the pawls may be released from the teeth in the upper edges of the plates 44.

Two vertical plates 51 are secured to the sides of the cars 10 respectively. Each of said plates is provided with a horizontal arm 52 which extends laterally and is provided with a depending projection 53 which is disposed between the upper sides of the two adjacent belts 28. Two horizontal bars 54 are mounted one each between the belts 28 of each pair of chain belts, the ends of each bar 54 being secured to opposite ones of the belts of each pair. When a pair of the belts 28 are driven in the direction indicated by the arrow in Fig. 6, the bar 54 carried by said pair of belts will engage the projection 53 disposed between said belts and will force the adjacent car 10 forward and upward on its track toward the retorts 1. The tube 16 carried by said car 10 will be moved forward lengthwise, together with the screw 19 in said tube, in the adjacent tube 14. If prior to this ore has been fed into the tube 16 through the feed opening 17, and the screw 19 has previously been rotated so as to force the ore forward, the tube 16 will have been filled with ore. If now the tube 16, after being forced forward in the tube 14 is retracted, and at the same time the feed screw 19 is rotated in the proper direction, the ore in the tube 16 will be discharged into the tube 14. By then stopping rotation of the screw 19 and again forcing the tube 16 forward in the tube 14, the charge which has been deposited in the tube 14 will be discharged into the re-

tort 1 to which the forward end of the tube 14 is at that time connected. I have described how the tube 16 is forced forward, and now I will describe how the tube 16 and car 10 carrying said tube is moved downward and rearward away from the retorts 1.

On each car 10 is mounted the following described mechanism, so that a description of one of said mechanisms will suffice for both. 10 On the car 10 is provided a bearing 55 to which is pivoted an upright lever 56, the upper end of which is bifurcated and engages opposite sides of the adjacent sleeve 39 in a peripheral groove 57 provided in each sleeve 39 adjacent its forward end. To the lower end of the lever 56 is secured one end of a substantially horizontal spring 58, the other end of which is secured to a vertical pin 59 secured to the car 10 to the rear of said lever 56. The tension of the spring 58 is such that the lever 56 will be swung forward at its upper end, thus retracting the sleeve 39 out of engagement with the adjacent bevel gear 37. The following described mechanism is provided to 20 swing the lever 56 in the opposite direction, or the one in which the sleeve 39 will be forced into engagement with the hub of the gear wheel 37. Pivoted near its center to the plate 51 is a lever 60, to the lower end of which is secured one end of a cord 61, which cord passes from said lever rearwardly to a pulley 62 mounted on the under side of the car 10, thence transversely and horizontally to a pulley 63, also rotatively mounted on the underside of the car 10, thence over the pulley 63 and rearward to the lower end of the lever 56 to which it is secured. As soon as the car 10 has moved forward so that the tube 16 and feed screw 19 therein acting together as a piston, will have forced the charge out of the tube 14 into the adjacent retort, the bar 54 will pass over the sprocket supporting stud 30 and will be carried by the belts 28 below and out of engagement with 30 the adjacent projection 53 with which said bar 54 has been engaged during the forward movement of the car 10. As soon as the bar 54 passes rearward of the stud 30 it will strike the upper end of the lever 60, which at 40 this time will have arrived just to rear of the sprocket wheels 29, as denoted by dotted lines in Fig. 6. The lever 60 will have been swung forward at its upper end by the spring 58 and cord 61, the sleeve 39 thus being moved forward out of engagement with the hub of the bevel gear 37. As the bar 54 strikes the lever 60 the lever will be swung by said bar to the position shown in solid lines in Fig. 6, and thereby forcing the sleeve 39 into engagement with the hub of the bevel gear 37, as before described. The feed screw 19 will thus be rotated in a direction such that the ore will be forced forward toward the retort in the tube 16. As the bar 54 is 50 carried rearward by the chains 28 to which it

is attached, the car 10 which has been moved forward will be moved rearward, the lever 60 being held by the bar 54 in the position shown in solid lines in Fig. 6, and the feed screw thereby being rotated will cause the ore to be discharged into the tube 14 as the car 10 and tube 16 are retracted by the pressure of the bar 54 on the lever 60.

To release the bar 54 from the lever 60 when the car 10 has been retracted to the position shown in Fig. 6, the following described mechanism is provided. Two upright posts 64 are secured at their lower ends to the upper side of the plate 6, said posts 64 being disposed respectively adjacent the sides of the cars 10 to which are secured the plates 51. To the upper end of each post 64 on the side adjacent the plate 51 are secured the ends of two horizontal studs 65 and 66 on which are rotatively mounted respectively two rollers 67 and 68 disposed so that the lower part of the belts 28 run between and respectively upon the lower side of the roller 67 and upon the upper side of the roller 68. The rollers 67 and 68 are so disposed that when the upper end of the lever 60 passes below the roller 67, the chain belts which at this place incline rearward and upward at their lower parts, will carry the bar 54 above the lever 60, thus releasing the car 10 from the rearward impelling movement of the chain belts 28, and the car will be brought to rest by chock blocks 69 disposed so as to strike the rear wheel of the car 10, said chock blocks being secured one to each rail 9. As the lever 60 is released from the bar 54, said lever will be swung forward to the position shown in dotted lines in Fig. 6, by the spring 58 and cord 61, said spring also swinging the lower end of the lever 56 so as to disengage the sleeve 39 from the hub of the gear 37, and rotation of the feed screw 19 will thus be discontinued until the car 10 has been again moved forward as before described.

In order that the cars 10 may be moved forward and backward, the plate 7 is provided with two openings 70 through which the hoppers 18 extend, said openings being long enough parallel with the track rails 9 to permit the desired forward and rearward movement of said cars 10.

I will now describe the mechanism by which the support carrying the retort charging means is vertically adjusted on the car 3 so that the horizontal rows of retorts may be successively charged.

Referring particularly to Figs. 1 and 2, 71 denotes four ropes secured at one set of ends to the plate 7, said ropes passing from the plate 7 upward and over four pulleys 72 respectively, which pulleys are rotatively mounted in the plate 5. Attached to the other ends of said ropes respectively are four weights 73 which serve to substantially counterbalance the weight of the support for 125 130

the retort charging means and the apparatus carried by said support. Secured to the plate 7 at their lower ends are four ropes 74 which pass upward from the plate 7 to and over four pulleys 75 respectively rotatively mounted in the plate 5 near the posts 4 respectively. Said ropes 74 pass horizontally from the pulleys 75 to and over four pulleys 76 rotatively mounted in the plate 5 near its central portion. From the pulleys 76 said ropes extend downward and are secured at their lower ends to the periphery of a drum 77 rotatively mounted in vertical bearings 78 secured to the upper side of the plate 7. The drum 77 is provided with a crank arm 79 by which the drum may be rotated to wind or unwind the ropes 74 for the purpose of raising or lowering the support comprising the plates 6 and 7 and posts 8. Secured to one end of the drum 77 is an axially mounted ratchet wheel 80 the teeth of which are engaged by a pawl 81 pivoted to one of the supports or bearings 78 and by means of which the drum is releasably held against rotation in one direction.

In operating my invention the car 3 is moved along the track 2 to a position in which the two tubes 14 are disposed in vertical alinement with two vertical rows of retorts, preferably the two vertical rows at the right, as viewed in Fig. 2. The crank arm 79 is then rotated in a direction such that the supporting plates 6 and 7 and the apparatus carried thereby will be moved vertically into a position in which the two tubes 14 will be in alinement with the lower row of retorts 1. The levers 46 are then swung so as to engage the forward ends of the tubes 14 with the first two retorts at the right in the lower row, as viewed in Fig. 2. In the meantime the tubes 16 will have been filled with ore as before described. The motor 21 is then started again, thus driving both sets of chain belts 28, which belts by means of the bars 54 attached thereto will engage the projections 53 and force both cars 10 forward, thus forcing the charges from the tubes 14 into the two retorts with which the tubes 14 are at this time respectively connected. The bars 54 will then engage the levers 60, thus forcing the cars 10 rearward and at the same time causing the feed screws 19 to rotate and force fresh charges into the tubes 14 from the tubes 16 as the tubes 16 are retracted rearward. When the cars 10 have reached the chock blocks 69, the bars 54 will have been released from the levers 60, and rotation of the feed screws 19 will cease. The motor 21 is then stopped, and the levers 46 are swung so as to 60 retract the tubes 14 from engagement with the two retorts. The car 3 is then moved to the left, as viewed in Fig. 2, until the tubes 14 are disposed in vertical alinement respectively with the next two vertical consecutive rows, after which the operation just described

is repeated. These operations are continued until all of the retorts in the lower row have been charged, after which the drum 77 is rotated so as to elevate the charging mechanisms into horizontal alinement with the next 70 higher horizontal row of retorts. The retorts in this row are then charged in the manner already described, the car 3 being moved alternately to the right and left, and the charging mechanisms being elevated one row 75 at the end of each horizontal row.

As the retorts are charged their mouths may be covered with suitable closures, such as fire clay caps 82, two of which are shown in Fig. 1.

The cars 10 may be provided with any suitable brakes of ordinary construction, shoes 83 of which only are shown in Fig. 6.

Having thus described my invention, what I claim and desire to secure by Letters Patent, is:

1. The combination with a horizontally movable car, of a support mounted on said car, an inclined track on said support, a second car mounted on said track, and a retort charging means carried by said second car.

2. The combination with a horizontally movable car, of a support mounted on said car, means for vertically moving said support on said car, an inclined track on said support, a second car mounted on said track, and a retort charging means carried by said second car.

3. The combination with a horizontally 100 movable car, of a support mounted on said car, an inclined track mounted on said support transversely to the path of movement of said car, a second car mounted on said track, and a retort charging means carried 105 by the second car.

4. The combination with a horizontally movable car, of a support mounted on said car, means for vertically moving said support on said car, an inclined track on said support disposed transversely to the movement of said car, a second car mounted on said track, and a retort charging means carried by the second car.

5. The combination with a conductor 115 adapted to connect with the mouth of a retort, of a reciprocative device, means for reciprocating said device, means by which when said device is moved in one direction a charge is deposited in said conductor, and means by which when said device is moved in the opposite direction said charge is discharged from said conductor.

6. The combination with a conductor 125 adapted to connect with the mouth of a retort, of a car carrying said conductor, and means by which when said car is moved to and fro said conductor is alternately charged and discharged.

7. The combination with a conductor 130

adapted to connect with the mouth of a retort, of a car carrying said conductor, means for moving said car to and fro, and means by which when said car is so moved said conductor will alternately be charged and discharged.

8. The combination with a conductor adapted to be connected with the mouth of a retort, of a car carrying said conductor, means for moving said car to and fro, means by which when said car is so moved the conductor will be alternately charged and discharged, and means for moving said conductor lengthwise.

15. 9. The combination with a car movable horizontally, of a second car carried by the first and movable transversely to the movement of the first car, a conductor carried by the first car and adapted to be connected with the mouth of a retort, and means by which when said second car is moved to and fro on the first car the conductor will be alternately charged and discharged.

10. The combination with a car movable horizontally, of a support mounted on said car, a conductor carried by said support, a second car movable to and fro on the first car transversely to the movement of the first car, means for so moving the second car, and means by which when said second car is moved to and fro said conductor will alternately be charged and discharged.

11. The combination with a car movable horizontally, of a support mounted on said car, means for vertically moving said support on said car, a conductor carried by said support and adapted to be connected with the mouth of a retort, a second car movable to and fro on said support transversely to the movement of the first car, means for so moving said second car, and means by which when said second car is so moved the conductor will be alternately charged and discharged.

45. 12. In retort charging mechanism, the combination with a tube adapted to be connected with the mouth of a retort, of a second tube having telescopic connection with the first tube and provided with a feed opening, ejecting means in the second tube, means for reciprocating the second tube, and means by which when the second tube is being moved in one direction, the ejecting means will be operated.

55. 13. In retort charging mechanism, the combination with a tube adapted to be connected with the mouth of a retort, of a second tube having telescopic connection with the first tube and provided with a feed opening, a feed screw disposed longitudinally in the second tube, means for reciprocating the second tube lengthwise, and means by which when the second tube is moved lengthwise in one direction the feed screw will be rotated.

65. 14. In retort charging mechanism, the com-

bination with two tubes reciprocatively mounted one in the other, one of said tubes having a feed opening and the other adapted to be connected with the mouth of a retort, a feed screw mounted in the inner one of said tubes, and means for rotating said feed screw.

15. In retort charging mechanism, the combination with two tubes reciprocatively mounted one in the other, one having a feed opening and the other adapted to be connected with the mouth of a retort, means for separately reciprocating said tubes lengthwise, a feed screw disposed lengthwise in the tube having the feed opening, and means for rotating said feed screw.

16. In a retort charging mechanism, the combination with a car movable horizontally, of a support carried by said car, two tubes reciprocatively mounted one in the other, one tube having a feed opening and the other adapted to be connected with the mouth of a retort, said tubes being each reciprocative lengthwise on said support transversely to the movement of said car, means for reciprocating said tubes in said manner, an ejecting means mounted in the tube having the feed opening, and means by which when the tube having the feed opening is moved lengthwise in one direction, the ejecting means will be operated.

17. In a retort charging mechanism, the combination with a car movable horizontally, of a support carried by said car, two tubes one reciprocative in the other, one tube having a feed opening, the other being adapted to be connected with the mouth of a retort, ejecting means mounted in the tube which is reciprocative, means for reciprocating said reciprocative tube lengthwise, and means by which when said reciprocative tube is moved lengthwise in one direction, the ejecting means will be operated.

18. The combination with a horizontally movable car, of a support carried by said car, a tube carried by said support, a track mounted on said support transversely to the movement of said car, a second car on said track, a tube mounted on said second car and having a feed opening and telescopic connection with the first tube, means for reciprocating the second car, ejecting means carried in the second tube, and means by which when the second car is moved in one direction on its track the ejecting means is operated.

19. The combination with a horizontally movable car, of a support carried by said car, means for vertically moving said support, a tube carried by said support, a track mounted on said support transversely to the movement of said car, a second car on said track, a tube carried by the second car, having a feed opening and telescopic connection with the first tube, means for reciprocating the second car, ejecting means carried in the second tube, and means by which when the second

car is moved on its track in one direction, the ejecting means is operated.

20. The combination with a horizontally movable car, of a support carried by said car, means for vertically moving said support on said car, a tube having a feed opening, an ejecting means carried in said tube, a second car mounted on said support for reciprocating said tube transversely to the movement 10 of the car, means for reciprocating the second car on said support transversely to the movement of the first car, ejecting means in said tube, and means by which the ejecting means is operated when the second car is moved on 15 said support in one direction.

21. The combination with a horizontally movable car, of a support mounted on said car, a second car transversely movable on the said support, a tube carried by the second 20 car and having a feed opening to receive the charge, a feed screw mounted in said tube, means for reciprocating the second car on said support, and means for rotating said feed screw when the second car is moved in 25 one direction on said support.

22. The combination with a horizontally movable car, of a support on said car, means for vertically moving said support, a second car movable on said support transversely to

the movement of the first car, means for reciprocating said second car, a tube carried by the second car and having a feed opening to receive the charge, a feed screw mounted lengthwise in said tube, and means for rotating the feed screw when the second car is 35 moved on its support in one direction.

23. The combination with a horizontally movable car, of a support on said car, means for vertically moving said support, a second car movable on said support transversely to 40 the movement of the first car, means for reciprocating the second car, a tube mounted on said support, means for reciprocating said tube lengthwise on said support, a second tube having telescope connection with the first tube and having a feed opening to receive the charge, the second tube being carried by the second car, a feed screw mounted lengthwise in said second tube, and means for rotating said feed screw when the second 45 car is moved in one direction.

In testimony whereof I have signed my name to this specification in presence of two subscribing witnesses.

HARRY CROCKER.
